INKING MECHANISM FOR ROTARY
PRINTING PRESSESThomas Ewart Phythian, Headingley, Leeds,
EnglandApplication September 24, 1931, Serial No. 564,863
In Great Britain October 8, 1930

3 Claims. (Cl. 101—351)

This invention relates to inking mechanism for printing machines of the type in which ink is by capillary attraction taken up by a rapidly rotating drum from the fountain roller for distribution and application to the printing cylinder or printing surface, and especially to inking mechanism of the kind described in the specification of application for British Letters Patent No. 331,570.

10 In such mechanism ink is continuously fed to the rapidly rotating ink drum so long as the rotary elements of the printing machine are in movement. If there are no plates on the plate cylinders of the machine the ink collects on the ink drums and ink rollers so that when plates are inserted and paper is fed through the machine an excess of ink is supplied over and above the requirements when the printing machine is set into operation. Further, in the event that 20 the paper web breaks, the paper may adhere to the ink rollers and ink drums and gather in the space between them.

The invention has for its object to avoid these disadvantages.

25 According to the invention the ink fountain is so mounted that it may be moved into and out of the operative position in relation to the ink fountain roller or the ink drum.

According to the invention, moreover, the ink 30 fountain roller may be so mounted in relation to the ink drum that it may be moved from its position of proximity thereto when it is not required to supply ink to the said ink drum.

According to the invention, moreover, the ink 35 fountain together with the ink fountain roller may be adapted for movement or adjustment of position to bring the ink fountain roller out of proximity to the ink drum.

According to the invention, also, the movement 40 of the ink fountain roller or of the said roller and the ink fountain may be effected at the moment when the inking rollers are moved away from the inking drum and may be effected by co-operating mechanism.

45 The invention further comprises the features of construction hereinafter described.

An example of inking mechanism in accordance with the invention is illustrated in the accompanying diagrammatic drawings.

50 Figure 1 is a side view of the mechanism.

Figure 2 is a view at right angles to Figure 1 showing certain parts of the mechanism.

In carrying the invention into effect according to a particular construction, the ink fountain 55 a is pivotally mounted upon an axis b parallel

with the axis of the fountain roller a^1 and to the rear thereof and is supported adjacent to or forward of the ink fountain roller by a link or connecting rod c which passes loosely through a clearance hole in a swivel pin a^3 mounted in the wall of the fountain a or in a lug or bracket a^2 provided thereon and has a screw-threaded portion to receive a nut or nuts c^1 serving to confine a helical buffer or cushioning spring c^2 coiled thereon below the swivel pin a^3 . The upper end of the link or connecting rod c is suitably coupled as by a clamping plate and bolts to the strap d^1 of an eccentric d provided upon a spindle e adapted to be rotated through 180°, for example, by a handle or other operating mechanism f , so that the lower end of the link or connecting rod c is raised or lowered, as the case may be, to the extent of twice the eccentricity of the eccentric d to bring the fountain a into and out of the operative position. The 75 said means of support for the fountain a may be duplicated at the two ends thereof.

The operative position of the ink fountain roller a^1 in relation to the corresponding inking drum may be readily determined and adjusted by 80 means of an adjusting screw or stop g mounted in a bracket h of fixed position and adapted to bear upon the fountain body or a lug or bracket a^2 thereon, such as that carrying the swivel pin a^3 through which passes the link or connecting rod 85 c . Thus, according to the adjustment of the said stop g , the fountain a will be arrested in its upward movement irrespective of the possible continuing upward movement of the link or connecting rod c , with the consequent increase of compression of the buffer or cushioning spring c^2 .

The spindle or shaft e carrying the eccentric d may be the shaft whereby a movement is given to the frame i carrying the inking rollers j to move these out of contact with the ink drum k or out of engagement with the plate cylinder or the like. Thus, the frame i may be connected to parallel rods l which are coupled by fixed links m in which are provided bearings for the spindle e . The latter may have fixedly mounted upon it an eccentric n , the strap of which is pivoted at o to the machine frame. When the handle f is operated the partial rotation of the spindle e causes the complete assembly to move laterally 100 with respect to the pivots o to withdraw the inking rollers j .

It will be understood that when the fountain roller a^1 is mounted in the fountain a it will be subjected to the movements given to the fountain 110

a. The invention may, however, be carried out by providing for the fountain roller a^1 , together with the scraper blade and mechanism, to be given a movement relatively to the fountain, which may be of fixed position. In this case the bearings of the fountain roller a^1 and the parts associated with it will be connected to a mechanism such as that hereinbefore described, for example, and be caused to move under constraint, 10 as in slideways.

It will further be understood that the operation of the mechanism effecting the desired movement of the fountain, or of the fountain roller, may be coupled by suitable mechanism to the 15 tripping mechanism of the printing machine, to ensure that in the event of breakage of the web the supply of ink to the ink drums is cut off.

I claim:—

1. Inking mechanism for rotary printing 20 presses, comprising inking means consisting of an ink fountain and a fountain roller, the said ink fountain being mounted for a limited movement of rotation in both directions about a pivotal axis, an operating eccentric with axis parallel 25 with the said pivotal axis of the fountain, means for suspending said fountain from said eccentric, an inking drum fed by the said fountain roller, a main inking drum and inking rollers co-operating therewith, the said fountain being moved on operation of the eccentric to separate the fountain roller from the inking drum fed by it and to return it into engagement therewith, and means for 30 separating the inking rollers from the main inking drum and returning them into contact therewith, said means comprising a rotary element 35

with which the eccentric effecting the movement of the ink fountain is in operative connection.

2. Inking mechanism for rotary printing 80 presses, comprising inking means consisting of an ink fountain and a fountain roller, an inking drum fed by the said fountain roller, a main inking drum and inking rollers contacting therewith, a control element revolvable in two directions about a fixed axis for throwing said inking rollers out of contact with the said main inking drum, a 85 pivotal support for one of the elements of the said inking means, and a second support for the said element linked to the control means whereby movement may be imparted from said control means to separate the fountain roller from the inking drum.

3. Inking mechanism for rotary printing 90 presses, comprising inking means consisting of an ink fountain and a fountain roller, the said fountain being adapted for movement about a pivotal axis, an inking drum fed by the said fountain roller, a main inking drum and inking rollers contacting therewith a control element revolvable in two directions about a fixed axis, a link connecting said ink fountain to said control 95 element for imparting a movement of rotation to the said ink fountain in both directions about the said axis to separate the fountain roller from the inking drum and to return it into engagement, and means for supporting the inking rollers 100 from the main inking drum and returning them into contact therewith, said means comprising a control element in operative connection with the control element of the ink fountain.
